UNITED STATES PATENT OFFICE.

GUSTAF DAVID SUNDSTRAND AND OSCAR J. SUNDSTRAND, OF ROCKFORD, ILLINOIS,
ASSIGNORS TO THE SUNDSTRAND CORPORATION, OF ROCKFORD, ILLINOIS, A COR-
PORATION OF ILLINOIS.

ADDING AND LISTING MACHINE.

Application filed September 20, 1920. Serial No. 411,544.

The object of this invention, generally stated, is to provide an improved dial mechanism which will enable the operator to see at any moment the total amount which 5 has been accumulated in the machine.

To illustrate one of the advantages of having a dial mechanism on an adding machine, it may be stated that a firm may wish to deposit, say, about \$1,000 in each of several banks. By means of the dial mechanism the operator will know when he has added up checks to the amount of \$1,000 without the necessity of printing a subtotal from time to time. Thus the checks to be 15 deposited can be sent to the bank with a slip bearing a list of the amounts of the checks and the grand total, without any subtotals appearing on the slip.

In eighty-one-key machines it is a simple matter to provide dials to be read by the operator, inasmuch as the adding wheels may be provided on their peripheries with figures of ample size. This is possible because in eighty-one-key machines the adding 20 wheels are spaced so far apart that the wheels may have comparatively wide peripheries and still leave sufficient room for the carrying mechanism. In adding machines of the ten-key type, however, the adding 25 wheels are spaced so closely together that the peripheries of the adding wheels are too narrow to allow of placing legible figures thereon.

It is a particular object of this invention 30 to provide a dial mechanism for ten-key machines.

In adding machines which have heretofore been provided with dials, the latter have been located at the forward end of 35 the machine and relatively near the base thereof, whereas the printing is done at the upper rear portion of the machine. Hence the operator has been obliged to glance first at the dials and then at the printing 40 position, or vice-versa. It is an object of this invention to locate the dials close to the printing position so that the operator may read the amount shown by the dials 45 and the amount printed on the paper at practically a single glance.

Visible printing being a great desideratum, it is not desirable to place any sort of indicating mechanism where it will ob-

scure the item last printed. It is therefore an object of this invention to provide 55 a dial or total-indicating mechanism which shall be close to the printing position without obscuring the printed matter.

In the accompanying drawings Figure 1 is a view showing in side elevation much of 60 the mechanism of a machine embodying the present invention. Fig. 2 is a fragmental sectional view of the dial mechanism. Figs. 3 and 4 are longitudinal vertical sectional views. Fig. 5 is a front elevation of the 65 dial mechanism. Fig. 6 is a sectional view of the dial mechanism as viewed from the front of the machine. Fig. 7 is a plan view of the fingers 461 for holding the dial pinions against accidental rotation, and the 70 guides for the racks 455.

The embodiment which has been selected for illustration herein is generally similar to the ten-key adding and listing machine disclosed in Patent No. 1,198,487, granted 75 September 19, 1916, upon an application filed by Gustaf David Sundstrand, but it is to be clearly understood that the present invention is by no means limited to machines of this type.

Referring now to the drawings:

The sheet or tape on which the items and totals are to be printed may be supported in any ordinary or suitable way. Herein is shown a roll *a* of paper supported on a 80 carriage 1. Rotatably positioned on the carriage is a cylindrical platen 2. The printing is effected by means of vertically reciprocating bars 3; one such bar being provided for each numerical order. Each 85 bar is provided at its upper end with ten type-carrying plungers 9 adapted to print from naught to nine, respectively. The top plunger is adapted to print "0", the next to the top "1", and so on. The bars 3 90 may be reciprocated by any suitable means, as, for example, that fully disclosed in said Sundstrand patent, said means including a handle 27. The handle 27 swings on a fixed pivot 27^a which is carried by a bracket 27^b on the base of the machine. The handle 27^c is attached to a crank arm 27^d. Said crank arm is connected to a link 27^e which is pivoted to a crank arm 24 that is fixed 100 on a rock shaft 26.

The means for driving the type-carrying

plungers 9 into contact with the inked ribbon (not shown) comprises a series of hammers 100 (Fig. 2) one for each bar 3, which are pivoted on a rod 108 and are actuated by individual springs 109.

The adding mechanism comprises a series of adding pinions 125 rotatably mounted upon a shaft 126 which is carried by a frame 127 pivoted at 128. The pinions 125 (of which there is one for each bar 3) are adapted to mesh with rack teeth 129 formed in the bars 3. When an item is to be added the frame 127 is swung forward to disengage the pinions 125 from the racks 129 before the bars 3 are raised, and said frame is swung rearwardly just before the bars 3 are moved downwardly. Addition therefore occurs in the downward stroke of the bars 3, the extent of rotation of the pinions depending, of course, upon the extent of movement of said bars.

The frame 127 is swung to carry the pinions 125 into and out of mesh with the racks 129 by means of a lever 400 pivoted to the framework of the machine at 401. In the lever 400 is a cam slot 402 into which extends the end of the adding pinion shaft 126. On the lever 400 is a roller stud 404 that lies in a cam slot 405 in a lever 406. The lever 406 is pivotally mounted on the rock shaft 26 and has an arm 407 which is arranged to be engaged by a pin 408 on the arm 24. A coiled contractile spring 409 acting upon the arm 407 tends to move the lever 406 in the direction to move the pinions out of mesh with the racks. When the operator begins to pull the handle 27 forward, the pin 408 leaves the arm 407 and thereby allows the spring 409 to throw the pinions out of mesh with the racks. When the handle begins to return to normal position the pinions must be placed in mesh with the racks, which result is effected by the following described means:

On the lever 406 is pivoted at 410 a hook 411 which is acted upon by a spring 412. Said spring allows the hook to yield upwardly to permit a stud 413 on the crank arm 24 to pass on the forward stroke of the handle 27, said hook springing into engagement with the stud near the end of the forward stroke of the handle. During the early portion of the return stroke of the handle the hook 411 causes the lever 406 to move with the crank arm 24, thus throwing the pinions into mesh with the racks. At the proper point in the return stroke of the crank arm 24 the lever 406 is released therefrom through the rising of the hook 411 due to contact of a finger 414 on said hook with a relatively stationary part 415. When the hook 411 is thus disengaged from the stud 413 the lever 406 is prevented from swinging forward under the influence of the spring 409 by a latch 416 pivoted at 417, said latch

having a locking shoulder 418. A spring 419 tends to hold the latch 416 against a pin 420 (Fig. 4) on the arm 407. On the latch 416 is a finger 421 adapted to be engaged by the pin 408 on the crank arm 24. In the return stroke of the crank arm 24 the pin 420 passes under the locking shoulder 418 just before the hook 411 is disengaged from the arm 24. As the arm 24 finishes its back stroke the pin 408 engages the finger 421 and pushes the latch 416 out of engagement with the pin 420, the pin 408 then serving to hold the arm 407 down.

It will be seen that when addition is to occur the spring 409 throws the pinions out of mesh with the racks before the latter begin their upward movement, and that the pin 408 acting through the hook 411 throws the pinions into mesh with the racks just before the racks commence to move down.

It sometimes is desirable to print an item without adding it to the amount already accumulated. This may be accomplished by means acting to disable the hook 411 so that the pinions shall not be thrown into mesh with the racks at the beginning of the downward stroke. In the illustrated embodiment said means include a non-add key 152, the stem 153 of which has a pin 154 which is arranged to act upon the forward end of a lever 155. Preferably the pin 154 acts upon a yielding part carried by the lever 155. Herein the pin 154 is arranged to act upon a lever 155^a which is pivoted at 155^b to the forward end of the lever 155. A spring 155^c acting upon one arm of the lever 155^a holds said lever in normal position, the action of said spring being limited by the contact of a lug 155^d on the lever 155^a with the lever 155. The lever 155 is pivotally supported on a fixed pivot rod 145 which is carried by the bracket 27. The rear end of the lever 155 underlies a pin 156 on the hook 411. When the operator depresses the non-add key 152 the rear end of the lever 155 lifts the hook 411 and holds it elevated so that when the crank arm 24 makes its return stroke the pin 413 does not engage the hook 411. The pinions therefore stay out of mesh with the racks until the pin 408 by pressing against the arm 407 moves the pinions into mesh with the racks, the latter by that time having reached their normal (lower) position.

The carrying or transfer mechanism may be of any suitable character, as, for example, that fully disclosed in said Sundstrand patent. In the construction shown in said patent when an amount is to be carried from one order to the next higher order, the bar 3 belonging to such higher order descends below its normal position, the extent of such excess descent being just sufficient to turn the adding pinion for that bar through the distance of one tooth.

When a total is to be printed the pinions

are retained in mesh with the racks during the upward movement of the latter. To retain the pinions in mesh with the racks when the handle 27 is pulled forward, there is provided a latch 174 pivoted at 417, the lower end of said latch being adapted to overlie the pin 420 and thus hold down the arm 407 when the handle 27 and the crank arm 24 make their forward stroke. As explained in the Sundstrand patent, when the total is to be printed, a spring (not herein shown) holds the latch 174 in position to hold the pinions in mesh with the racks.

For reasons pointed out in the Sundstrand patent, when a total is to be printed those racks which mesh with the pinions standing at zero cannot rise, the remaining racks rising until the rotation of their pinions is stopped by the transfer dogs (not herein shown), said pinions then being at zero. The bars 3 are then in position to print the total amount accumulated on the pinions.

When it is not desired to clear the machine after printing a total, the pinions are allowed to remain in mesh with the racks during the downward movement thereof, and consequently during the downward movement of the racks the several pinions are rotated to the positions they occupied just before the taking of the total. When, however, the operator wishes to clear the machine, the pinions are withdrawn from the racks before the latter descend, thus leaving all of the pinions standing at zero. This is accomplished by withdrawing the latch 174 from the pin 420 just before the racks descend. Said latch is withdrawn by means comprising a total key 177, the stem 408 of which has a stud 179 that underlies the forward end of a lever 422. The lever 422 has an elongated opening 423 through which the pivot rod 145 extends. It will be seen that the lever 422 is movable longitudinally to a slight extent. A contractile spring 424 tends to slide the lever 422 rearwardly. On the rear portion of the lever 422 is an inclined or cam surface 425 arranged to engage and force rearwardly a pin 426 on the latch 174. A contractile spring 427 connected to the forward end of the lever 422 tends to raise the rear end of said lever into engagement with the pin 426. To lock the lever 422 in the position just mentioned and to restore the lever to normal position there is provided a lever 428 which is pivoted to the framework of the machine at 429 and which overlies a pin 430 on the rear end of the lever 422. The lever 428 has a slot 431 therein to receive the pin 430. A spring 432 connected to one arm of the lever 428 tends to swing the lever 428 to pass the slotted portion of said lever into engagement with the pin 430. The rear end of the lever 428 is arranged to be engaged by a rod

22 carried by two arms 20 and 21 depending from a shaft 12. The rod 22 is connected to the crank arm 24 by means of a link 23. When the handle 27 returns to normal position, the rod 22 moves rearwardly and forces the lever 428 down, the upper wall of the slot 431 forcing the pin 430 down (see Fig. 1).

It will be seen that when the machine is to be cleared the pulling forward of the handle and the depression of the total key 177 permits the spring 427 to tilt the lever 422 into engagement with the pin 426, thereby withdrawing the latch 174 from the pin 420. In order to prevent the spring 409 from throwing the pinions out of mesh with the racks as soon as the latch 174 is disengaged from the pin 420 and before the hammers 100 have effected the printing of the total, there is provided a stud 433 on the lever 406 adapted to be engaged by the slotted portion 434 of the lever 422. When the lever 422 is swung to disengage the latch 174 from the pin 420, the slotted portion 434 engages the stud 433 before said latch is disengaged.

A plate or lever 435 pivoted at 429 has a cam slot 436 in which the rod 22 travels. In said lever is a notch 437 to receive the pin 430. When the handle 27 is pulled forward and the total key depressed, the spring 427 places the pin 430 in the slot 431 and the notch 437. During the return stroke of the handle, the rod 22 acts on the lever 435 to cause the rear wall of the notch 437 to push the pin 430 and consequently the lever 422 forward far enough to disengage the pinions from the racks, this action occurring after the hammers 100 have been fired and before the racks have started to descend. In the continuing return movement of the handle, the lever 428 forces the lever 422 down out of engagement with the lever 406, and restores said lever 422 to normal position (see Fig. 1).

The dial mechanism comprises a set of dial wheels 450 (Fig. 6) rotatably mounted upon a shaft or pivot rod 451 carried by a bracket or housing 452. Said housing is pivoted to the framework at 453. Rigidly attached to each dial wheel is a pinion 454 adapted to mesh with a rack bar 455 fixed to the forward edge of and extending parallel with the adjacent bar 3. The pinions 454 may be moved into and out of mesh with the racks 455 in any suitable manner as by rocking the housing 452. In the present embodiment of the invention, the housing 452 is rocked by means of an arm 456 fixed to said housing and having a roller stud 457 that lies within a cam slot 458 in the upper portion of the lever 400.

Since each dial rack is rigidly connected to an adding rack, and since the adding pinions and the dial pinions are thrown into

mesh with their respective racks simultaneously, and likewise are moved out of mesh synchronously, it will be evident that every 5 rotative movement imparted to an adding pinion will be imparted to the corresponding dial pinion. The dial wheels therefore will at all times represent the total that is represented by the adding pinions. Inasmuch as the carrying movements are imparted to the adding pinions by the racks 10 129, and said racks are rigid with the dial racks 455, a single carrying mechanism serves for both sets of wheels, and the dial wheels may be made of maximum peripheral 15 width.

By reference to Fig. 1, it will be noted 20 that the dial mechanism is located close to the printing position, but does not obstruct the operator's view of the printed matter. The housing 452 is located forward of the type bars and the platen, and between the platen and the keyboard. The housing has 25 a sight opening 459 (Figs. 2 and 5) through which the operator may see the horizontal row of figures constituting the total accumulated in the adding wheels. The case 460 that encloses the machine has a glazed sight opening (not shown) which registers with the sight opening 459.

When the dial pinions are out of mesh 30 with their racks, they are held against accidental rotation by fingers 461 (Figs. 2, 6 and 7) carried by a stationary plate 462, said fingers extending between the teeth of 35 the pinions when the latter are out of mesh with the racks.

It is desirable that the type bars be guided 40 or held against lateral movement relatively close to the printing line in order that the impressions shall not be laterally displaced through lateral movement of the type bars. The present construction provides guides for the type bars directly above the hammers so that the type bars are held or effectively 45 guided and prevented from moving sidewise. It will be noted that in the rear edge of the plate 462 are slots 463 in which the racks 455 are guided, said slots thereby also assisting to hold the upper ends of the type bars 50 3 against lateral displacement.

In the present embodiment the guiding of 55 the upper ends of the type bars is effected by means of the slotted plate 462. The same result might be attained by making the dial wheels of such diameter that the racks would always lie between the dial wheels whether the pinions were in or out of mesh with the racks, in which case the dial wheels would serve to prevent lateral movement of the 60 racks. If desired, dial wheels of sufficiently large diameter to serve as guides for the racks may be employed in addition to the slotted guide plate 462.

The forward portion of the plate 462 is 65 bent downwardly and provided with slots

464 which serve to guide the hammers 100 and hold each hammer in the vertical plane of its series of types 9.

Inasmuch as we believe ourselves to be the first to provide a dial mechanism or other 70 total-indicating means for visible printing ten-key adding and listing machines, we desire the appended claims to be construed broadly.

We claim as our invention: 75

1. A ten-key adding and listing machine having, in combination, a keyboard; printing mechanism comprising vertically reciprocatory type bars, a platen behind the type bars, and hammers in front of the type bars 80 to drive the type to print; adding mechanism operated by said type bars; a pivoted housing located in front of the type bars and behind the keyboard; a series of total dial wheels located in said housing above said 85 hammers, said housing having a sight opening in its forward side to expose the dial wheels; a pinion connected to each dial wheel; a rack on the upper end of each type bar; and means connecting said housing to 90 the adding mechanism to place said pinions in and out of mesh with said racks.

2. A visible-printing ten-key adding and listing machine having, in combination, a keyboard; printing mechanism comprising 95 vertically reciprocatory type bars, a platen behind the type bars, and hammers in front of the type bars to drive the type to print; adding mechanism operated by said type bars, a pivoted support located in front of 100 the type bars and above and behind the keyboard; a series of total dial wheels carried by said support above said hammers; a pinion connected to each dial wheel; a rack on the upper end of each type bar; and means 105 connecting said support to the adding mechanism to place said pinions in and out of mesh with said racks.

3. A ten-key adding and listing machine having, in combination, a keyboard; printing mechanism comprising type bars, a platen behind the type bars, and hammers in front of the type bars to drive the type to print; adding mechanism operated by said type bars; a pivoted support located in front 110 of the type bars and behind the keyboard; a series of total dial wheels carried by said support above said hammers; a pinion connected to each dial wheel; a rack on the upper end of each type bar; and means connecting said support to the adding mechanism to place said pinions in and out of 115 mesh with said racks.

4. A ten-key adding and listing machine having, in combination, a keyboard; printing mechanism comprising type bars, a platen behind the type bars, and hammers in front of the type bars to drive the type to print; adding mechanism operated by said type bars, said mechanism including adding 120 125 130

racks operatively related to the type bars; a pivoted support located in front of the type bars and behind the keyboard; a series of total dial wheels carried by said support 5 above said hammers, a pinion connected to each dial wheel; a second set of racks, each rack being operatively connected to one of the adding racks; and means connecting said support to the adding mechanism to place 10 said pinions in and out of mesh with the second set of racks.

5. In an adding and listing machine having, in combination, a key board, a set of vertically reciprocatory type bars mounted 15 behind said keyboard, and racks on opposite

ends of each type bar, an adding mechanism associated with the lower racks, and a total indicating mechanism disposed between said type bars and said keyboard and comprising a set of dial wheels, a pinion connected 20 to each dial wheel and means for moving said pinions into and out of engagement with said upper racks whereby said dial wheels will at all times indicate totals accumulated in said adding mechanism. 25

In testimony whereof we have hereunto set our hands.

GUSTAF DAVID SUNDSTRAND.
OSCAR J. SUNDSTRAND.
